UNITED STATES PATENT OFFICE

ADOLPH PETELER, OF FREEPORT, NEW YORK, ASSIGNOR TO AUTO SPECIALTIES MANUFACTURING CO., OF SAN FRANCISCO, CALIFORNIA, A CORPORATION OF CALIFORNIA

JACK

Application filed October 10, 1925. Serial No. 61,654.

This invention relates to lifting jacks and more particularly to jacks of the type employing a lifter bar operated by a hand lever, as shown in my Patent Number 1,393,242, 5 granted October 11, 1921.

The device herein set forth comprises a toothed lifter bar which by reason of lifting and holding pawls associated with other elements may be raised or lowered under the action of a hand lever.

The present invention provides a lifting jack comprising the usual lifting and holding pawls associated with a toothed lifter bar. The lifting pawls are actuated by the manual 15 manipulation of a hand lever. The holding pawl or detent serves to retain the lifter bar in position during each successive stage in the elevation of a load. In addition to the lifting mechanism, the invention contem- 20 plates other movable elements for effecting a reverse step by step movement of the lifter bar or for permitting a continuous drop of the lifter bar. The elements for causing the last-mentioned operations may be provided 25 as separate units manufactured so as to be applied to the other elements of the jack in a cheap and labor-saving manner. This unit which serves as a mechanism to change the direction of movement of the lifter bar, may 30 be termed a reversing mechanism.

The reversing mechanism may comprise a bearing plate having journaled thereto a lever member in operative relation to the holding pawl of the jack; a cam member engageable 35 with the said lever member and with the lifting pawl or detent of the jack; also a reversing lever for cooperation with the cam member. The reversing lever serves as a control for throwing the reversing mechanism into 40 operation.

For the purpose of making my reversing mechanism applicable to a jack it is only necessary that the pawls of the jack be provided with studs projecting through slots in the 45 main casing or housing of the jack. The jack may be completely assembled in so far as the lifting and holding mechanism is concerned and the reversing unit may also be assembled with the several movable elements thereof 50 pivotally mounted on the journal plate of

the unit. The journal plate is then secured to the main housing of the jack with the reversing mechanism in the proper relation to the lifting and holding pawls of the jack.

Considerable advantage is derived from 55 this construction since a jack constructed according to my invention may be quickly and conveniently assembled. By having the journal plate carry all the reversing mechanism, the elements thereof may be arranged and 60 mounted in a simple jig; the holes for the pivot pins being drilled or punched in a single operation and movable members may be easily adjusted to position on pins extending through the holes and the pins riveted over, 65 thus making the reversing unit complete for application to the jack proper.

It will thus be evident that a jack constructed by the usual method may be improved by the addition of reversing mechanism with but a small increase in cost above 70 that entailed to produce the usual non-reversing jack.

An object of the present invention, is, 75 therefore, to provide a reversible jack of simple construction and at a low cost.

Another object of the invention is to provide a reversing mechanism applicable to a lifting jack without material alteration 80 thereof.

Another object of the invention is to provide a reversing unit of a cheap and simple construction which may be applied to a lifting jack at a minimum cost.

Another object of the invention is to facilitate the manufacture of a reversible lifting jack by mounting the reversing mechanism independently of the lifting mechanism.

Another object of the invention is to provide a jack-reversing mechanism, the movable elements of which may be readily adjusted and retained in their adjusted positions.

Other objects of the invention will become 95 apparent as the following description is read.

The invention will be more clearly understood by reference to the accompanying drawing in which

Fig. 1 is a side elevational view of a jack 100

of the type to which the present invention may be applied.

Fig. 2 is an edge view of the jack shown in Fig. 1 but showing in dotted lines the journal plate and cover of my reversing mechanism.

Fig. 3 is a side view of the jack with the elements of the reversing mechanism in position, the cover therefor having been removed.

Fig. 4 is a fragmentary view of the jack-reversing mechanism showing the elements thereof in another position.

Fig. 5 is a view showing the journal plate and the various movable elements in different positions to change the positions of the holding pawl and detent, and

Fig. 6 is a view taken on line VI—VI in Fig. 4.

The selected embodiment illustrated here-with may comprise a standard 10 having a casing 11 at the upper portion thereof to enclose a lifter pawl 12, a holding pawl 13, and a toothed lifter bar 14.

The lifter bar may be slidable vertically within the casing 11 and provided with a head or saddle 15. A stop member to prevent removal of the lifter bar may comprise a lip 15' formed from a wall of the housing 10. The lip 15' may be bent inwardly to extend into a groove 17' of the lifter bar and may be engageable with a pin 18' when the lifter bar has reached the limit of its upward movement. Suitably disposed teeth 16 may be provided on the lifter bar, the teeth being movable in operative relation to the pawls 12 and 13.

The lifter pawl 12 may be pivoted on a pin 17 at one end of a short arm 18 of a lever 19, which lever may be pivoted on a fixed pin 21 and may have a long arm 22 extending from the casing 11. The arm 22 may be constructed in the usual manner to receive an extension piece (not shown). The holding pawl 13 may be pivoted on a pin 23 secured to walls of the casing 11. The pawls 12 and 13 are normally held in engaging position with the teeth 16 of the lifting bar under the action of a spring 24. This spring serves as a common means for moving the pawls and as shown may be in the form of a continuous piece of spring wire. The wire may encircle the pivot posts of the pawls and ends 25 and 26 may engage projecting studs 27 and 28 secured to and projecting laterally from the pawls 12 and 13, respectively. The stud 27 may extend through a slot 29 in the casing 11 and the stud 28 may extend through a slot 31.

The mechanism above described will operate to lift a load placed upon the saddle 15 and to hold the load in an elevated position.

For the purpose of attaining a reverse or downward movement of the lifter bar 14, mechanism (see Figs. 3 and 4) including a double arm lever member 32, a cam member

33 and a reversing lever 34, are provided. These elements may be mounted as a unit on a journal plate 34' (see Figs. 5 and 6). The lever member 32 may be rotatable about a pin 35. The cam member may be rotatable about a pin 36 and the reversing lever may be pivoted on a pin 37. The journal plate may be provided with raised portions or bosses 35', 36', and 37' as bearing surfaces for the members 32, 33, and 34, respectively. These bosses also serve to provide space for the respective springs for the said members, thus avoiding the necessity of providing a hub on the movable members and permitting the members to be punched and formed from sheet metal.

The pins which serve as pivots for the several elements of the reversing mechanism may, as shown, be provided with suitable heads at ends thereof, the opposite ends being upset or riveted over in the usual manner to retain the members in operable relation on the journal plate 34'. This plate may be provided with extensions or ears 38 and 39 having holes 41 and 42 arranged to coincide with tapped holes 43 and 44 in the casing 11 whereby the journal plate 34' may be secured to the casing. When the reversing unit is fastened to the casing the studs 27 and 28 extend through apertures 45 and 46 in the journal plate 34'. The stud 27 is thus positioned in operative relation to an arm 55 of the cam member 33 and the stub 28 in operative relation to an arm 48 of the lever member 32. The lever member is provided with a spring 49 which normally urges an end of an arm 48 of the lever member against the stud 28 and as the spring 49 is stronger than the spring 24 the lever member, when free, may act to retain the holding pawl 13 from engagement with the teeth 16 of the lifter bar 14. When the lever member is free to act, therefore, the lifter bar may be dropped by disengaging the lifter pawl 12 from the teeth 16 to lower the bar when no load is being supported as will be later described.

As shown in Fig. 4, however, when the jack is to be actuated to elevate a load the cam member 33 is oscillated to bring arm 47 thereof into engagement with an arm 52 of the lever member 32, causing a release of the holding pawl and permitting it to act under the energy of spring 24 to engage with the teeth 16 of the lifter bar. The cam member 33 is actuated by the reversing lever 34, a cam arm 53 of which makes contact with an offset straight surfaced flange 54 at an end of an arm 55 of the cam member 33. The reversing lever is also provided with a straight surfaced end 56 which, as shown in Fig. 4, when engaged with the flange 54, serves to lock the cam member in engaging position with the lever member 32 in opposition to the action of a spring 57, acting to cause a movement of the arm 47 of the cam

member away from engagement with the arm 52 of the lever member 32. A stop piece 50 which may be integral with the edge of the aperture 45 is provided to limit the movement of the cam member 33.

5 The stud 27 projects from the casing 11 and an end thereof is disposed in the path of movement of the arm 55 of the cam member 33 but out of the path of travel of the arm 53 of the reversing lever 34, the flange 54 being provided so that the reversing lever may engage the cam member while out of the plane of the body thereof.

10 The action of the stud upon the cam member is to provide for the step by step lowering of the lifter bar when a load is supported thereon.

15 If the reversing bar is left positioned as shown in Fig. 3 and a load is carried by the 20 jack, the engagement between the detent 13 and a tooth of the lifter bar will retain the detent 13 in position to support the load although the lever member 32 is exerting a force to remove the detent. When in this position, 25 a downward movement of the lever 19 will cause the lifting pawl to raise the lifter bar and release the detent which instantly disengages from the lifter bar. This movement of the lifter bar obviously occurs while the 30 lifter pawl is engaged with a tooth of the bar and the said pawl is moved upwardly. A downward movement of the pawl causes the stud 27 thereof to engage with a rounded surface 55' of the cam member 33 effecting 35 a movement of this member causing it to engage with the lever member 32. The lever member is thus released from engagement with the detent 13 and the same immediately returns and engages with a tooth of the lifter bar. The engagement between the stud 27 40 and the curved surface of the cam member is however, momentarily effective for the purposes above mentioned since as the stud traverses the curved surface in a downward direction and the cam member is released, by 45 this time the detent has of course engaged with a tooth of the lifter bar and the load thereon results in sufficient frictional engagement to prevent the lever member 32 under 50 the action of its spring from removing the detent until as above set forth the lifter bar is raised by a downward movement of the lever.

55 It will be noted that the curved surface of the arm 55 of the cam member 33 engages with the stud 27 when the hand lever 19 is raised when the elements are in the position shown in Fig. 5. By reason of the said curved surface the lifter pawl is disengaged from 60 the teeth of the lifter bar. This action occurs when the lever member 32 is free to move the detent 13 from engagement with the teeth of the lifter bar assuming that the said bar does not support a load. The free movement of 65 the lifter bar is thus evident. Therefore, if

no load is carried, the detent will not be held in engagement with the teeth 16 owing to the action of the spring 49 of the lever member 32 and the lifter bar will drop when the lifting pawl is moved out of engagement with the teeth of the lifter bar by an actuation of the lever 19 as shown in Fig. 5.

70 A suitable cover plate 58, as shown in Fig. 2, may be provided to enclose the reversing mechanism, a slot being formed to allow for the movement of the hand piece 61 of the reversing lever.

75 As shown, the present invention provides a reversible jack which may be constructed to a great extent of stamped or pressed metal by punch and die operations. Furthermore, the assembly of the parts is greatly simplified. The jack is easily operated and when desired the lifter bar may be freely moved upwardly or downwardly, a load being thus lifted or lowered step by step at will or the bar may be dropped.

80 The control of the holding pawl by changing its operative relation to the lifter bar is accomplished by the simple reversing mechanism shown.

85 Although a preferred embodiment of the invention has been described and illustrated, it is obvious to those skilled in the art that modifications thereof may be made, however, 90 it is contemplated by me to include such modifications as come within the spirit and scope of the invention as defined by the appended claims.

95 What is claimed is:

100 1. A lifting jack comprising a toothed lifter bar, a holding detent, a hand lever with a lifting pawl pivoted thereon, a spring for normally pressing the detent toward said lifter bar, a pivoted lever member engageable with said detent, a spring for rocking said lever member about its pivot to move the detent away from said lifter bar, a pivoted double arm cam-member having one 105 arm engageable with the lever member, a reversing lever to engage with the other arm of the cam member to actuate the same and cause an actuation of the lever member.

110 2. A lifting jack comprising a toothed lifter bar, a holding detent, a hand lever with a lifting pawl pivoted thereon, a spring for normally pressing the detent toward said lifter bar, a pivoted lever member engageable with said detent, a spring for actuating said lever member to hold the detent away from the lifter bar, a pivoted cam member engageable with said lever member, a reversing lever, said cam member being disposed intermediate to and in operative relation with said lever member and said reversing lever.

115 3. A lifting jack comprising a toothed lifter bar, a holding pawl, a lifting pawl, tensional members for normally pressing said pawls toward said lifter bar, a hand 120

125

lever associated with said lifting pawl to effect an upward movement of said lifter bar, a stud projecting from each of said pawls, reversing mechanism comprising a double arm lever pivoted adjacent to said holding pawl, a spring for normally rotating said lever to move one arm thereof into contact with the stud of said holding pawl, said spring having a greater force than the tensional member of said holding pawl, a cam member pivoted adjacent to said lifting pawl, said cam member having a cam arm and a lever arm, a spring for normally moving said cam member to urge an arm thereof out of contact with the other arm of said double arm lever, the cam arm of said cam member being disposed in the path of movement of the stud in said lifting pawl and a pivoted member having an extended portion thereof engageable with the cam arm of the cam member to actuate said reversing mechanism.

4. Reversing mechanism for a lifting jack having a toothed lifter bar and holding detent normally disposed in engagement with said bar, said reversing mechanism comprising a journal plate, a lever member, a cam member, and a reversing lever pivoted in operative relation upon said plate, said plate being attachable to said casing to position said members in operative relation to the detent of the jack, means for normally urging the lever member into contact with said detent, and means on said reversing lever for locking the same in engagement with said cam member to hold the lever member out of engagement with said detent.

5. Reversing mechanism for a lifting jack having a casing, and lifting means within the casing, said lifting means including a toothed lifter bar and a holding detent, said mechanism comprising a journal plate, a lever member a cam member and a reversing lever pivoted in operative relation upon said plate, said plate being attachable to said casing to position said members in operative relation to the outwardly extending portions of said lifter means.

6. A lifting jack comprising a toothed lifter bar, a holding detent, a stud upon said detent, a hand lever with a lifting pawl pivoted thereon, a stud upon said pawl, a spring for normally pressing the detent toward said lifter bar, a pivoted lever member engageable with the stud on said detent, a spring for rocking said lever member to engage and hold the detent away from the lifter bar, an oscillatory cam member engageable with said lever member to rock the same upon engagement with said detent, a reversing lever engageable with said cam member to oscillate the same to cause a disengagement of said lever member with said detent, and an arcuate surface upon said cam member engageable with the stud on said pawl to cause

a movement of the pawl away from the lifter bar when the hand lever is lifted.

7. A lifting jack comprising a toothed lifter bar, a holding detent, a spring for normally moving said detent toward the teeth of said lifter bar, a hand lever with a lifting pawl pivoted thereon, reversing mechanism for said jack including a double arm lever number having one arm engageable with the detent, a pivoted double arm cam member having one arm engageable with said lever member and the other arm having an arcuate surface, a reversing lever engageable with the last-mentioned arm of said cam member, the arcuate surface of said arm serving to guide the lifting pawl from engagement with the rack upon a downward movement of said pawl causing the load to be supported on said detent, and a spring for said lever member.

8. In combination with a jack including a casing, a toothed lifter bar slidable therein, a pivoted hand lever, and a lifting pawl and a detent cooperating with said lifter bar to effect a step by step projectile movement thereof during oscillation of said handle, a detachable support plate mounted in said casing, a reversing mechanism comprising a plurality of cam member pivoted in the support plate in position to co-operatively inter-engage, and a cam control lever pivoted in said support plate, certain of said pivoted members being arranged to engage and control the pawls for causing said pawl and detent to effect a step by step retractile movement of said lifter bar during oscillation of said handle.

9. In combination with a jack including a casing, a projectile and retractile lifting bar and means to effect a step by step projectile movement of said bar, said means having portions projecting from the casing, a reversing mechanism comprising a detachable plate mounted in said casing, a plurality of cam members pivoted in the support plate in position to co-operatively inter-engage and a cam control lever pivoted in said detachable plate, certain of said pivoted members being arranged to engage and control the projecting portions whereby to co-operate therewith to cause the same to effect a step by step retractile movement of said bar, said reversing mechanism being formed as a unit separate from said jack and being attachable to and detachable from said jack casing as a unit.

10. In combination with a jack including a projectile and retractile lifting bar and means to effect a step by step projectile movement of said bar; a reversing mechanism attachable to and detachable from said jack as a unit, said mechanism consisting of a plate and a plurality of pivoted control cams carried thereby arranged to cooperate with each other and with the step by step bar pro-

jecting means of the jack when the mechanism is attached to the latter to cause said projecting means to effect a step by step retractile movement of said bar and means pivoted in said plate for manipulating said control cams.

11. In combination with a jack including a casing, a projectile and retractile lifting bar supported in the casing, means for affecting a step by step projectile movement of said bar, said means having portions extending through the casing and reversing mechanism comprising a pivoted cam member having a portion arranged to engage a projecting portion of said means for effecting, step by step, projectile movement of the bar, a second pivoted cam member having a portion adapted to engage a second projecting portion, and a portion adapted to co-operate with said first mentioned pivoted control member whereby to release it from contact with said first mentioned projecting portion, and a control lever adapted when in one position to engage and fasten said second mentioned pivoted cam to cause the same to release the projecting portion of said means and to engage the first mentioned cam to cause it to release the corresponding projecting portion of said movement causing means.

12. The reversing mechanism for a lifting jack having a casing, a lifter bar arranged in the casing for projection therefrom and lifting means arranged within the casing and adapted to project and retract the lever bar, said lifter means having portions projecting through the casing, said reversing mechanism comprising a journal plate adapted for attachment to said casing, control members pivoted in operative relation upon said plate and in position to co-operate with each other projecting portions of said lifter means, said journal plate being provided with bosses on which said members are journaled.

13. A lifting jack comprising a casing, a toothed lifter bar supported in the casing, a holding detent, a hand lever, a lifting pawl actuated by the hand lever, said hand lever and said holding detent being pivoted in the jack casing, and a spring arranged to normally urge the holding detent and the lifting pawl into engagement with the lifter bar, a reversing mechanism for controlling the holding detent and the lifting pawl, said mechanism comprising members normally urged to operative position by spring means of sufficient strength to counteract the effect of the first mentioned spring, and means for locking said members against the normal urge of said spring means.

14. In a jack a casing, a toothed lifter bar arranged for axial projection and retraction in the casing, means for actuating said lifter bar including a lifting detent, a holding detent and a spring normally urging said detents toward operative position, and control

means for governing the operation of said detents whereby to cause the lifter bar to be projected or retracted at will, said control means comprising a journal plate detachably mounted to said casing opposite the said detents, a spring pressed control cam lever for said holding detent carried in said journal plate in position to engage and normally urge said lifting detent away from operative position, a second spring pressed control cam lever having a portion normally positioned to engage and control said lifting detent to move in a pre-determined path during its operative movement, said second cam member being rotatable to release said lifting detent for movement along another pre-determined path, and having a portion to co-operate with the first or holding detent control lever, whereby upon movement of the former to release the lifting pawl, the latter is moved to release the holding pawl, and a pivoted lever for moving and locking said second pivoted control cam.

In testimony whereof I affix my signature.

ADOLPH PETELER.
